TO ECONOMIC MACHINERY COMPANY, OF WORCESTER, MASSACHUSETTS, A COR-
PORATION OF MASSACHUSETTS.

FEED-SPACER MECHANISM FOR CAN-LABELING MACHINES.

1,281,315.

Specification of Letters Patent.

Patented Oct. 15, 1918.

Application filed November 24, 1917. Serial No. 203,706.

To all whom it may concern:

Be it known that we, ARVID P. EKVALL and HERMAN STAKE, both citizens of the United States, residing at Worcester, in the county of Worcester and State of Massachusetts, have invented certain new and useful Improvements in Feed-Spacer Mechanism for Can-Labeling Machines, of which the following is a specification.

10 Our present invention relates to means for successively feeding cans or similar articles or containers into can-labeling or like machines; the prime object being to provide an efficient mechanism for delivering rolling cans or the like, in serial order at regular spaced intervals, and in rapid succession.

Another object is to provide a mechanism of the character specified, with means for preventing disarrangement in the space intervals when a can is not present for regularly taking its place in the series, and for synchronizing the timing of delivery intervals in relation to the action of the succeeding mechanisms in the affixment of labels.

25 The nature, construction and mode of operation of our invention is explained in the following detailed description; the particular subject matter claimed being hereinafter definitely specified.

30 In the accompanying drawings, (two sheets) Figure 1 represents a section elevation view of our can-feeding and spacing mechanism, and such parts of a can-labeling machine as will illustrate the nature of our invention. Fig. 2 is a plan view of the same. Figs. 3, 4 and 5 represent vertical sectional views of the mechanism, showing the parts at various stages of their action. Fig. 6 is a separate detail view of the spacer devices. Fig. 7 is a vertical sectional view of the back of the spacer device, separate from other parts.

In the drawings, R indicates the rollway for cylindrical cans, or the like, which are 45 delivered thereto by an inclined chute or conveyer A, of any desired length, upon which the cans are placed manually or otherwise. The chute is preferably hinged to the rollway, as at a. B indicates the overlying 50 propeller belts of usual form, mounted upon pulleys B⁺ (only one pair of which is shown) and operated by the shaft 9 to rotate in the direction indicated by arrow; and may re-

ceive power and motion from any approved source.

D indicates the overhead or top frame upon which the belt-pulley and feed mechanism are supported. In practice said frame is adjusted up or down to accommodate different sized cans.

P indicates the yieldingly mounted presser rollers arranged across the lower run of the belts, as heretofore employed, and C the cans in their passage in the mechanism.

Numeral 10 indicates the label-holder or box for containing the supply pack of labels L, which are supported on an elevator plate 11; the top of the pack being maintained substantially level with the roll-way by any approved automatically acting means combined with the elevator standard 12.

13 indicates the primary can-gumming roll; 14 the sprocket chain or means for rotating said rolls from a wheel upon the operating shaft 9; and 16 denotes the side 75 guides between which the cans travel in their progress through the machine. E indicates the contacting member of the lap-end gumming appliances, which may be of any suitable character, preferably adapted to act at uniformly timed intervals.

At a convenient position adjacent the front of the belt-supporting pulley B⁺, we provide an oscillating plate or spacer element 20 arranged across the feed-delivery 85 chute above the path of the incoming cans, and is connected by suitable ears 2 with a transversely disposed axis-member or shaft 21 mounted in bearings 19 upon the forward part of the overhead frame D, or some equivalent support. The height of the spacer 90 above the surface upon which the cans C roll, is approximately equal to the diameter of the can. The under surface of the spacer element (see Fig. 6) is preferably arched 95 from its front to its rear edge, or made in the form of a cylindrical segment; the curvature of the arc being of equal or somewhat greater radius than the outside curvature of the largest sized cans to be operated upon. The under side of the spacer element 20 is adapted for approximately embracing a segment of the cylindrical upper surface of the can, somewhat in the manner of a saddle, or as a can-housing member, for maintaining 105 the can in accurate transverse relation upon

the rollway; said spacer element is tilttable or rockable for alternately elevating its front and rear edges for admitting and releasing the can contained thereunder. Said 5 spacer is longitudinally straight and arranged transverse of the rollway, parallel with the position of the can, and is provided on its upper side at or near the rear edge with bearing lugs 3 in which there is mounted 10 a rockable shaft 23, parallel with the supporting shaft 21. The spacer 20, or its axis shaft 21, has rigidly connected therewith a projecting arm 17 provided with a stud-roll 17* that engages with a cam 24 arranged 15 upon and revolving with the operating shaft 9 of the belt-carrying pulley B*. A suitably tensioned spring 7 is combined with the arm for keeping the end of the arm or its stud-roll up against the cam, and for moving the 20 spacer 20 as controlled thereby. The general shape of the cam 24 is indicated by dotted lines on Figs. 1, 3, 4 and 5. A portion of its periphery is, in the present instance, formed on a circular arc similar to that of 25 the pulley B*; but it may be varied or made of larger or smaller dimension if in any instance so required.

The arm 17 may be fixed or pinned upon the axis shaft 21, or attached to the spacer- 30 plate which is preferably pinned upon the shaft, so that said spacer is oscillated by movement of the arm, or in equivalent manner. Said arm, in the present instance, serves as the complement of lug 3, and has 35 the bearing for the shaft 23 formed therein.

Numerals 4 indicates intercepting fingers or detents fixed upon the rocking shaft 23 and projecting downward to a position for contact with the passing cans; and 5 indicates an upwardly projecting pawl or catch-detent adapted for locking engagement with a stationary stud 25 having a lug or notch in its side with which the end of the pawl catches when swung sufficiently far back. 40 (See Figs. 3 and 6.) The fingers 4 and pawl 5 are best pinned, or otherwise firmly secured, upon the shaft to rock in unison. A spring 6 is provided for normally acting upon the shaft for swinging forward the 45 fingers 4 and the pawl 5 backward to engaging position. Said spring may be located at any convenient position. As herein shown it is strained between an arm projecting from the shaft 23 and a stay on the 50 edge of the plate 20, as best illustrated in Fig. 6.

Numeral 27 indicates a friction band arranged about a pulley upon the shaft 9, which may be the broadened rim of the propeller belt pulley B*, or a special pulley located adjacent thereto, as at 26. Said band extends around suitable guide pulleys 29 and 30 disposed in bearings upon the top frame in such relation that the lower stretch 55 of said band passes adjacent to the spacer

element, and runs in contact with the rim or surface of the can C thereunder, and to the operating pulley, with sufficient friction upon the can for starting or impelling the same to roll forward to and under the propelling belt B, at a speed corresponding therewith, as soon as released by the spacer element 20; thus giving a positive start that puts the can beneath the propeller belts without liability of delay. 70

The lines III, IV, and V on Fig. 6, indicate positions of the arm 17 corresponding to the positions in views Figs. 3, 4 and 5. 75

In the operation: If there is no can in the feed-way, as when starting up the machine, 80 or if a can is absent from the approaching line in the chute, then when the swell of the cam presses down the arm 17 the pawl 5 is carried below the stud 25 and is swung by the action of the spring 6 and rocking shaft 85 23 to a position behind the lug on stud 25, so that as the receding portion of the cam comes around the pawl engages therewith temporarily locking the fingers 4 in position for intercepting or arresting a later 90 coming can when beneath the spacer 20, and detaining it until the proper relation in action is attained. The front edge of said spacer element is lifted and its back edge depressed when the arm 17 is forced down 95 by the cam 24. Fig. 3 shows the pawl at a position just before unlocking, and Fig. 4 is at a position after it has unlocked.

In normal running action the cans are placed in the inclined chute A, in any convenient manner, so as to roll down to the spacer mechanism in continued supply. The first can C enters beneath the arched spacer while the front edge is elevated, and may be there detained until the spacer is oscillated 105 rearward on its axis 21. The adjacency of the spacer element to the top of the cylindrical can requires an oscillative movement of the spacer to enable the can to pass beneath it. As the reduced portion of the cam comes around it allows the spring 7 to lift the arm 17, thus raising the rear edge of the spacer and freeing the can at a predetermined time, so that the friction band 27 will positively roll the can under the 110 propelling belts B, and depressing the front edge of said spacer to contact with, and arrest the second can C*, and those following (see Fig. 5) until the arched spacer element is oscillated to its primary receiving 115 relation by the swell of the cam, pressing down the arm. In like manner successive cans are individually released at spaced intervals of distance and time corresponding to the revolutions of the controlling cam, 120 acting synchronous with other parts of the machine. 125

During the time, if any, that a can is retained by the spacer 20, the band 27 will slip on the surface of the can. The for- 130

ward movement of a can is delayed only until the proper instant for its delivery, or until the preceding can has reached the predetermined interval of space therefrom.

- 5 When cans come to the spacer mechanism in an irregular manner, or with greater or less width of spaces between them, then if not in the exact proper space relation, as the front edge of the spacer is lifted, the
 10 can may pass into contact with the fingers 4; which, under such condition, are always found temporarily locked by the pawl 5, so that said fingers intercept and momentarily detain the can until it assumes the correct
 15 working relation in respect to oscillating spacer; at which position the pawl becomes unlocked and the can becomes released as above described; the movement of the can readily pressing back the fingers 4 which are
 20 then subject only to the slight resistance of the spring 6. By this means derangement in the space intervals is obviated, and the delivery intervals are synchronized with relation to the timing and space intervals in
 25 the action of the label-affixing means or succeeding parts of the machine to which our invention may be applied.

We claim and desire to secure by Letters Patent—

- 30 1. A feed-spacer mechanism for can-labeling machines, comprising, in combination, with a horizontal roll-way, a slightly inclined feed-way connecting therewith, traveling can-propelling belts overlying said roll-way, and belt-carrying pulleys and shafts; of a spacer member including an oscillatable cylindric segment extending transversely across the feed way and having a concave under face approximately con-
 35 formed to the height of, and for overlying the top surface of the cylindrical can rolling thereon, an axis-shaft by which said member is dependingly supported for swinging its front and rear edges alter-
 40 nately upward to permit the reception and exit of a rolling can thereunder, connections for oscillating said spacer member, and means in connection with the propeller-belt operating-shaft for controlling said oscil-
 45 lation.

- 50 2. In combination, with a run-way for rolling cans, can-propelling belts supported above said run-way to travel in contact with the upper surfaces of the cans rolling there-
 55 on, and means for operating said belts; a feed-delivery spacer of the character specified, including an axially supported can-housing member arranged transversely across and adjacently above the path of the
 60 cans and adapted for embracing the cylindric upper part of a can between front and rear parallel edge portions of said member, said housing member being oscillatable for bringing its front and rear portions alternately to positions for admitting, con-

fining, and releasing the incoming cans, a revolving cam and connecting means for oscillating said spacer, and means for impelling the respective cans from the spacer to beneath the propelling belts.

70

3. In a can labeling machine having a rollway and overlying can-propelling belts; the combination, of a movable spacer device adapted for engaging and regulating the passing of cans at the feed delivery, and 75 a frictional band acting against the exterior of the can passing said spacer device, said band extending in coacting relation to the can-propelling belts, and running adjacently coincident with the periphery of the 80 pulley carrying said belts.

4. In a can feeding mechanism, including an inclined chute and roll-way for cylindrical cans, can-propelling belts, and belt-carrying pulleys; a spacer mechanism comprising, in combination, a horizontally journaled arched rocking guard adjacently overlying the path of the cans at a position that requires a rocking oscillation of said guard to permit a can to pass beneath it, means for 90 intermittently rocking said guard, an oscillating finger-device mounted upon the rear edge of said rocking guard, and provided with depending fingers engagable with the can, an engaging stop controlled 95 by contact of the can with said guard finger device, and means for imparting oscillative motion to said rocking guard at predetermined intervals, substantially as set forth.

5. In a can labeling machine, the combination with a feed-way for rolling cans, can-propelling belts, pulleys therefor, and the operating shaft carrying said belts; of a transversely fulcrumed spacer device including a backwardly and forwardly tilttable element overlying the feedway path and adapted for its front and rear edges contacting alternately with a can rolling along said feed-way, an actuating arm for said tilttable element, a controlling cam therefor, operated from the shaft that carries the propeller belts, and means for rolling the released can beneath the propelling belts.

105 6. In a can labeling machine, the combination with a rollway for cans, can-propelling belts, belt-carrying pulleys, an operating shaft and the supporting frame therefor; of an oscillating spacer-device adjacently overlying the path of the cans, means adapted for alternately depressing its front 110 and rear portions into the path of the advancing cans, a rockable shaft mounted upon said spacer-device, downwardly projecting fingers carried by said shaft, a catch-pawl fixed on said shaft, a stationary lug for engagement of said pawl, and a spring connected for normally turning said rockable shaft to bring the fingers into downwardly projecting relation and yieldable to the passing cans when the catch-pawl is released, 115 120 125 130

- and means acting synchronously with the labeling operations for oscillating said spacer-device to deliver the cans at corresponding regular spaced intervals.
6. 7. In mechanism for the purpose described, the combination with a roll-way for cans, a top frame, overlying can-propelling belts, and belt-operating shaft and pulleys; of a spacer element disposed above the 10 path for the cans, and having depending front and rear portions arranged to require tilting action to allow a can to pass, a traverse axis-shaft having said spacer element secured thereon, bearings for said axis-shaft upon the top frame, an attached arm for tilting said shaft and spacer element, a spring connected therewith and a cam mounted upon the belt-operating shaft for controlling the action of said arm to tilt 15 said spacer element, backwardly yielding depending fingers having pivotal support upon the spacer element, a catch-device connected with the finger-supporting axis, an engaging-lug for temporarily retaining the catch-device with said fingers extended, a spring for moving said fingers to normal position, and means for positively advancing the cans to the propelling belt.
- 20 8. In a feed controlling spacer for can machines, an arched spacer-plate arranged adjacently above the path of the cans, an oscillating axis shaft having said spacer-plate fixed thereon, bearings for said shaft upon the overhead frame, a projecting cam-engaging arm connected for oscillating said spacer plate, a lifting spring attached to said arm, a cam for controlling the oscillative move-

ment of said arm and spacer-plate, said cam mounted to revolve with the belt-carrying pulleys, a friction band passing adjacent to 40 said spacer-plate and in contact with the rim or surface of the can, an actuating pulley carrying said band operating coincident with the propeller belt-carrying pulleys, in combination with the rollway, 45 can-propelling belts and belt-carrying pulleys.

9. In a can-labeling machine, including a rollway for cans, overlying belts for propelling the cans along said rollway, an overhead frame, an operating shaft with pulleys mounted thereon for carrying said propelling belts; the combination of a spacer means consisting of a pivotally suspended tiltable platen element extending transversely across the path of the cans, its center at a height from the rollway approximately equal to the diameter of the can, and having a concaved under side adapted for embracing a segment of the cylindrical upper surface of the can, said element being tilttable for receiving, retaining and releasing the can surmounted thereby, means for actuating said spacer element including a spacer-controlling cam rotating in unison with the 55 pulleys carrying the propeller belts, a counter acting spring and means for giving a forward impetus to the released can.

Witness our hands this 22nd day of November, 1917. 70

ARVID P. EKVALL.
HERMAN STAKE.
